UNITED STATES PATENT OFFICE.

CHARLES A. FOX, OF NEW YORK, N. Y.

COLLAPSIBLE BOX.

Application filed January 9, 1925. Serial No. 1,436.

To all whom it may concern:

Be it known that I, CHARLES A. Fox, a citizen of the United States, residing at New York city, county of New York, and 5 State of New York, have invented certain new and useful Improvements in Collapsible Boxes, of which the following is a specification.

This invention relates to improvements in 10 receptacles and has particular reference to a collapsible box.

An object of the present invention is to provide an improved box of simple and inexpensive construction in which the walls 15 of the sections thereof are so formed and assembled as to reduce to a minimum the amount of material wasted in the construction of the box and to provide a box which will be adequately reinforced against 20 collapsing when in use.

Another object is to utilize a portion of the intermediate section of the box which is interposed between the top and bottom sections thereof to provide locking elements 25 capable of engaging one of the walls of the bottom section to aid in maintaining the latter walls in operative position.

The above and other objects will appear more clearly from the following detailed 30 description, when taken in connection with the accompanying drawings, which illustrate preferred embodiments of the inventive idea.

In the drawings—

35 Figure 1 is a perspective view of one form of the invention with the box in partially closed position;

Figure 2 is a vertical sectional view therethrough;

40 Figure 3 is a plan view of the box illustrated in Figure 1, showing the same in its collapsed position; and

45 Figure 4 is a transverse section through the box taken substantially on the line 4—4 of Figure 2.

The form of the invention shown in the accompanying drawings is illustrated in connection with what is generally known as the telescoping type of box, but it is to be expressly understood that said drawings are used merely for the purpose of illustrating the invention as a whole and not to define the limits thereof, reference being had to the appended claims for this purpose.

As shown, the box consists of bottom and

top sections generally indicated by the numerals 7 and 8, respectively, joined by an intermediate section 9 providing a hinge connection between the top and bottom section. 60

The bottom section 7 includes a front wall 10, side walls 11 having their front ends 12 overlapped and secured to the ends of the front wall 10, and a rear wall 13 which likewise has its ends 14 overlapped with the rear ends of the side walls 11 and secured thereto by suitable fasteners 14'. The side walls 11 and ends 14 are scored, as indicated at 15, so that the front and rear walls 10 70 and 13 may be collapsed as illustrated in Figure 3. The bottom edge of the rear wall 13 is provided throughout its length with a laterally extending reinforcing flange 16 which engages the bottom of the 75 section 7 to aid in maintaining the rear wall 13 in its operative position and preventing inward collapsing of said wall when the box is collapsed.

The top section also includes side walls 17 and a front wall 18 secured together and scored in the usual manner so as to permit of the section being collapsed, as shown in Figure 3, the rear wall of said top section being formed by the intermediate section 80 85 9 which acts as a further reinforcement for the rear wall 13 of the bottom section when the box is closed.

In accordance with the present invention it is proposed to provide further means for 90 maintaining the walls of the bottom section of the box in operative position and for this purpose the ends of the intermediate section 9, which form continuations of the side walls 11 and 17 of the bottom and top 95 sections, and which are scored, as indicated at 19, to permit of the folding of the sections as indicated in Figures 1 and 2, are cut to form locking elements or tongues 20 attached to the side walls 11 of the bottom section. When setting up the box these tongues are bent inwardly into engagement with the rear wall 13 and the free extremities of the tongues are inserted into angular slots 21 formed in said rear wall so as to 100 provide an interlocking engagement between the side walls 11 and said rear wall. 105

It is noted that the fasteners 14' all penetrate each of the side walls 11 and ends 14 below the folding lines 15 so that the 110 portion of each end wall above the folding line and adjacent the locking tongue will

be left unattached. This will permit of a free movement of the tongue in a vertical plane when being inserted into its slot 21 without placing any undue strain upon the 5 fasteners 14', as said upper portion of the wall 11 above the folding line may have a slight outward movement relative to the end 14 when said tongue is being manipulated prior to being engaged in its slot.

10. What is claimed is:

1. In a collapsible box, a bottom section including side walls and a rear wall having its ends overlapping said side walls, each of said side walls and the adjacent 15 overlapping end having folding lines to permit of collapsing said rear wall, fasteners extending through said overlapping ends and side walls only beneath said folding lines to permit of the portion of each 20 side wall above its folding line having an outward movement relative to the adjacent overlapping end of said rear wall, a top section, an intermediate section connecting said top and bottom sections, and locking

elements formed from the material of said 25 intermediate section and connected to said upper portions of the side walls above said folding lines and capable of being interlocked with said rear wall.

2. In a collapsible box, a bottom section 30 including side walls and a rear wall having its ends overlapping said side walls, means to secure the lower portion of each overlapping end to the adjacent side wall with the upper portion of said end and contiguous 35 portion of said side wall remaining unattached to permit of a relative outward movement of the latter portion of the side wall, a top section, an intermediate section connecting the top and bottom sections, and locking elements formed from the material of 40 said intermediate section and carried by the upper portions of said side walls and capable of being interlocked with said rear wall.

In testimony whereof I have affixed my 45 signature.

CHAS. A. FOX.
